UNITED STATES PATENT OFFICE.

HIRAM M. ROBERTS, OF VICKERY, AND JOHN FITZGERALD, OF PORT CLINTON, OHIO.

BOW-FACING OAR.

SPECIFICATION forming part of Letters Patent No. 643,980, dated February 20, 1900.

Application filed November 20, 1899. Serial No. 737,634. (No model.)

To all whom it may concern:

Be it known that we, HIRAM M. ROBERTS, of Vickery, Sandusky county, and JOHN FITZGERALD, of Port Clinton, Ottawa county, 5 Ohio, citizens of the United States, have invented certain new and useful Improvements in Bow-Facing Oars; and we do declare the following to be a full, clear, and exact description of the invention, such as will enable others skilled in the art to which it 10 pertains to make and use the same, reference being had to the accompanying drawings, and to the letters of reference marked thereon, which form a part of this specification.

15 This invention relates to improvements in bow-facing oars and rowlocks, and has for its object the providing of means for automatically causing the feathering of the oars and means for removably securing the rowlock to the gunwale of the boat.

20 This invention consists, essentially, in new and novel means for causing the oar to feather automatically and means for securing the rowlock to the gunwale; and the invention 25 further consists in the construction and novel arrangement of parts hereinafter described, illustrated in the drawings, and more particularly pointed out in the claims hereunto appended.

30 In the drawings, Figure 1 is a top plan view of the rowlock, showing the oar and actuating mechanism in position to take the water. Fig. 2 is a top plan view of a portion of the rowlock and actuating mechanism, 35 showing the oar in feathering position. Fig. 3 is a vertical sectional view of a portion of the rowlock, showing a portion of the detail construction of the device. Fig. 4 is a plan view of the rowlock, showing the oar and actuating mechanism in position at end of stroke. Fig. 5 is a detail of the oar-holding bracket; and Fig. 6 is a transverse view, 40 partly in section, showing portions broken away, illustrating the mechanism for automatically feathering the oar.

45 Referring to the drawings by letters, A indicates the gunwale of a boat, and B a suitable rowlock secured thereto in any suitable manner and provided with prongs or posts 50 B' B² at opposite ends thereof. This rowlock B is of any desired length and is provided on

its ends with reduced portions b b, adapted to fit or set in recesses in brackets C C', secured to the gunwale of the boat. The bracket C is provided with an undercut groove or 55 recess for the reception of one of the reduced ends of the rowlock, and the bracket C' is provided with an undercut recess c', having one side thereof open for the purpose of permitting one of the reduced ends of the rowlock to be slipped thereinto and also with a turnbuckle C², adapted to close the opening c' to hold the rowlock in position for use. In the prongs or posts B' B² are recesses or 60 seats b' b', into which set and rock a suitable 65 oar-support D.

b' is a tension-screw adapted to engage a convex seat in one end of the rockable support D to vary the tension thereof.

E is a bracket provided with the openings 70 or seats E' E' in the projections E² E³ and the ears e e. This bracket E is pivoted at the projection E³ at one end of the rockable support D, as shown at e'.

F is an oar upon which are fitted two collars f f', provided with bosses f² f³. These collars are so placed upon the oar that they will fit the openings E' E' and are for the purpose of preventing cutting of oars as they are turned for feathering. The collar f', fitting 75 on the inner end of the oar, is provided with a seat or channel f⁴, which passes through the boss f³ and registers with a suitable seat or channel in the end of the oar. The collar f is provided with a lug f⁵, that sets and runs 80 in a slot f⁶ in the projection E² of the bracket E for the purpose of limiting the rotation of the oar to about one-fourth of a revolution.

G is an angle-piece consisting of the arms g and g'. The arm g sets and is secured in 90 the seat or channel in the boss f³ and the end of the oar. The other arm g' is provided with a ball end g², adapted to fit into a socket h in one end of a link H. The opposite end of said link is provided with ears h' h'. 95

K is an oscillating lever pivoted at one end to the rowlock by the bolt K' and having its opposite end pivoted between the ears h' h' of the link H.

The bolt K' passes down into a chamber K² 100 in the rowlock B and is held cushioned therein by a spring K³, as shown, for the purpose

of permitting a slight tilting movement of the lever K and taking up the wear therein.

L is a bracket similar to the bracket E, and is pivoted to the opposite end of the rockable support D and has secured therein a lever M.

N is a suitable link connecting the brackets E and L at points on opposite sides of the rockable support D.

The operation of the invention is as follows:

- 10. The operation of the invention is obvious, the feathering operation being accomplished by depressing the lever M, which action lifts the blade from the water, at the same time automatically causes it to feather by the operation of the angle-piece G, which, oscillating in its socket, turns the blade of the oar from a vertical to a horizontal position. By slightly raising the lever M the blade is caused to resume a vertical position and take the water.

Having thus fully described our invention, what we claim is—

1. In a bow-facing oar of the character described, the combination of a rockable support, a two-part oar mounted thereon and connected by suitable levers, means for tensioning said rockable support, and mechanism, substantially as described, to give said oar-blade a horizontal, a vertical and rotary movement, as set forth.

2. In a bow-facing oar of the character described, the combination of a two-part oar, suitably connected, a rockable oar-support, means for tensioning said support, and mechanism, substantially as described, for automatically turning said blade when the oar-support is rocked, as set forth.

3. In a bow-facing oar of the character described, the combination of a rockable oar-support, means for tensioning said support, a two-part oar suitably mounted thereon, and connected by a suitable link, with levers connecting by a universal joint the end of the oar-blade with the rowlock, whereby the said blade may be automatically feathered when it is raised from the water at the end of a stroke, as set forth.

4. In a bow-facing oar of the character described, the combination of a rockable oar-support, a two-part oar suitably mounted thereon and connected by a suitable link; with a lever connected to a rowlock and a crank-piece connected to the end of the oar and connected with said lever by a universal joint whereby the said oar is automatically turned when the support is rocked, as set forth.

5. In a bow-facing oar of the character described, the combination of a rowlock, a rockable oar-support mounted therein, a lever pivoted near one end of said rockable support, an oar-holding bracket pivoted near the opposite end of said support and connected with said lever by a suitable link; an oar rotatably mounted in said bracket, and means for limiting the extent of rotation, with levers connected by a universal joint for rotating or turning said blade when the oar is raised from the water, whereby said oar is feathered when a stroke is made, as set forth.

6. In a device of the character described, the combination with a gunwale of a boat, undercut brackets secured thereon and a turn-button secured to one of said brackets, of a rowlock having reduced projecting ends adapted to fit into the undercut openings and be secured and immovably held therein by said turn-button.

7. In a bow-facing oar of the character described, the combination of a rockable oar-support, a two-part oar suitably mounted thereon and connected by a suitable link, with levers connecting the end of the oar-blade with the rowlock for automatically feathering said oar and spring mechanism for taking up the wear of the automatic feathering device, as set forth.

In testimony whereof we affix our signatures in presence of two witnesses.

HIRAM M. ROBERTS.
JOHN FITZGERALD.
